The ornamental design for an light emitting diode lamp, as shown and described.

DESCRIPTION

FIG. 1 is a first perspective view of an light emitting diode lamp incorporating a design according to the present disclosure;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
